UNITED STATES PATENT OFFICE.

WILLIAM H. BEVANS, OF WASHINGTON, DISTRICT OF COLUMBIA, ASSIGNOR
TO THE VICKERS SONS & MAXIM, LIMITED, OF SHEFFIELD, ENGLAND.

RAMMER FOR BREECH-LOADING GUNS.

SPECIFICATION forming part of Letters Patent No. 625,240, dated May 16, 1899.

Application filed February 28, 1899. Serial No. 706,522. (No model.)

To all whom it may concern:

Be it known that I, WILLIAM H. BEVANS, a citizen of the United States, residing at Washington, in the District of Columbia, have invented new and useful Improvements in Rammers for Breech-Loading Guns, of which the following is a specification.

My invention relates to a rammer for breech-loading guns so constructed that when not in use it occupies comparatively small space behind the gun, but for ramming it is rapidly elongated, so as to force the charge into the breech of the gun. For this purpose I construct the rammer as I shall describe, referring to the accompanying drawings.

Figure 1 is a longitudinal section of the rammer extended. Figs. 2 and 3 are longitudinal sections, to an enlarged scale, of the rear part and front part, respectively, of the rammer in its contracted condition. Fig. 4 is a transverse section on the line 4 4 of Fig. 3, the chains, rope, and their fixings being omitted.

a is a cylindrical casing, which is supported and fixed in any convenient position behind the gun, with its axis in line with that of the gun-bore. To the tube a are attached two side frames b b, having bearings for the axes of a winch, having a barrel c for a wire rope and a chain-barrel d. These axes are geared together, so that the barrel c makes four revolutions for each revolution of d. On the front end of the casing a is mounted a pulley e, around which passes a chain f, having its one end fixed to the barrel d and its other end fixed to the rear end of a tube g. On the front end of g is mounted a pulley h, around which passes a chain i, having its one end fixed to the front end of the tube g, while its other end is fixed to the rear end of a tube j. A similar arrangement of pulleys k and l and chains m and n is repeated for two other tubes o and p, and on p is fixed the rammer-head r.

At the front ends of the casing a and of the several tubes g, j, and o are fitted annular bushes q, and in the annular spaces between the casing and the several tubes, which are all concentric, are fitted linings s, so that all the tubes can slide telescopically. The

tubes are slotted along their lower sides to 50 accommodate the chains. To the rear end of the innermost tube p is fixed one end of a wire rope t, which passes around a pulley u, mounted on the rear end of the casing a, and has its other end attached to the barrel c. 55 When the rammer has to be elongated, the barrel c is turned in the direction of the arrow by a crank-handle w, the barrel d being turned at one-fourth of the speed in the opposite direction. As the chain f is wound on 60 the barrel d it causes the tube g to advance, thus drawing the chain i, causing the tube j to advance, and so on, the rammer-head r being thus moved forward. For retracting the rammer the barrel c is turned in the opposite direction, winding on it the rope t, and thereby drawing back the tube p and head r and the other tubes successively, the head r meeting the end of the tube o, shoulders x on the tubes o, j, and g meeting bushes q of 70 the tubes j and g and a, respectively.

Obviously instead of four sliding tubes, as shown in the drawings, there might be a less or greater number, the gearing of c to d being varied accordingly.

Having thus described the nature of this invention and the best means I know of carrying the same into practical effect, I claim—

A rammer for breech-loading guns comprising a tubular casing several concentric telescopedically-sliding tubes fitted with bushes and linings the innermost tube carrying a rammer-head, mounted on the casing a winch and a chain-barrel suitably geared together, guide-pulleys on the casing and on the tubes 85 except the innermost chains connecting the barrel to the outermost tube and the tubes to one another also a wire rope connecting the winch to the innermost tube substantially as and for the purpose set forth. 90

In testimony whereof I have hereunto set my hand in presence of two subscribing witnesses.

WILLIAM H. BEVANS.
